CONTAINER

John M. Hothersall, Brooklyn, N. Y., assignor to
 American Can Company, New York, N. Y., a
 corporation of New Jersey

Application July 2, 1936, Serial No. 88,660

9 Claims. (Cl. 229—23)

The present invention relates to a sealed fibre container having an opening element secured thereto by means of an adhesive seal and has particular reference to such a container in which the adhesive seal is restricted to a relatively small tearing area disposed adjacent a barrier which confines the zone of tear when the seal is broken in opening the container.

An object of the invention is the provision of a sealed fibre container having an opening element joined thereto by means of an adhesive seal wherein the sealed joint between container and opening element is restricted to a relatively narrow band which forms a small tearing area disposed adjacent one or more score lines cut in either or both of the joined parts to facilitate breaking of the seal when opening the container and to provide a barrier against spreading of the tearing area when the sealed joint is broken.

Another object is the provision of such a fibre container wherein the adhesive seal joint between container and opening element includes a removable area formed in one of the joined parts and which is defined by score lines which prevent spreading of the tearing area when the sealed joint is broken.

Still another object is the provision of a fibre container of this character having a tubular body made from a blank the ends of which are overlapped and secured together by a narrow band of adhesive forming a sealed joint therebetween and adjacent score lines cut in one or more of the overlapped parts of the blank to facilitate breaking the seal when opening the container and to provide one or more barriers against spreading of the tearing area when the sealed joint is broken, the score lines in the overlapped parts of the blank directing the zone of tear into other score lines cut in a wall of the body adjacent the opening element so that a portion of this wall is released to provide a hinged reclosure cover for the container after it is opened.

A further object is the provision of a fibre container having a tubular body of this character and having flanged end closure members one or more of which are adapted to be applied after the container is filled and are secured in place on the body, from the exterior, by locking indentations which are formed in the flanges of the ends and in the wall of the body after these parts are assembled, the indentations being produced by a shearing or cutting through of portions of the engaged walls and by a displacement of the stock contained between the shear lines so that the displaced parts are offset from the line of juncture.

Numerous other objects and advantages of the invention will be apparent as it is better understood from the following description, which, taken in connection with the accompanying

drawings, discloses a preferred embodiment thereof.

Referring to the drawings:

Figure 1 is a perspective view of a container embodying the instant invention and shows the container closed and sealed;

Fig. 2 is a perspective view similar to Fig. 1 and shows the container opened with its cover in raised position;

Fig. 3 is a composite or exploded plan view on an enlarged scale of a blank from which the container body is made and of two separate blanks from which end members are made, the end member blanks being shown graphically in a relative position to the body blank so that each is adjacent to what will become that end of the container to which it will be secured when the parts are assembled, the view showing the inner faces of said blanks;

Fig. 4 is a front elevation on an enlarged scale of the filled container shown in Fig. 1, with parts broken away;

Fig. 5 is an enlarged fragmentary section of the front upper portion of the container showing the parts in sealed position, the view being taken substantially along the line 5—5 in Fig. 4;

Fig. 6 is a view similar to Fig. 5 showing the same parts with the seal broken and the parts in partially open position;

Fig. 7 is an enlarged fragmentary section of a corner of the container showing how the end members are indented and locked with the container body, the view being taken substantially along the line 7—7 in Fig. 4; and

Fig. 8 is a transverse sectional detail taken substantially along the line 8—8 in Fig. 7.

As a preferred embodiment of the instant invention the drawings illustrate a container preferably comprising a rectangular body 11 (Figs. 1, 2 and 4) which is closed at the ends with end members 12.

The body is made from a flat blank 14 (Fig. 3) of fibrous materials such as paper, cardboard or the like and is formed with two parallel side edges 15 connected by irregular end edges 16, 17. The edges 16, 17 are also parallel one with another. Parallel score lines 18 are cut in one surface of the blank (this being the top surface as viewed in Fig. 3) adjacent its upper part as viewed in this figure, these lines being spaced inwardly from and parallel to the side edges 15.

The upper or outer end of each score line 18 connects with a short angular score line 21 which is spaced inwardly from the top edge 17 of the blank 14. The two score lines 21 are joined by a score line 22 which is located a relatively greater distance from the end of the blank than the lines 21.

Short score lines 25 (indicated by dotted lines) are also cut in the opposite or under surface of the blank 14 and are disposed close and parallel

to and outside of the score lines 18. Each score line 25 extends to the top edge 17 of the blank. Taken together each pair of score lines 18, 25 define a weakened section 26 in the blank.

- 5 At the bottom of the blank 14 adjacent its edge 16 spaced angular score lines 28, 29 (indicated by dotted lines) are cut in what is its under surface when considering Fig. 3, although this will be an exterior surface later. These score lines 10 are parallel to the score lines 21 at the upper edge 17 of the blank. The inner ends of the score lines 28, 29 are joined by parallel connecting score lines 31, 32. The score lines 28, 29 and 31, 32 enclose or define a removable area 33 in the 15 blank which may be readily torn away to a predetermined depth, this being the depth of the score lines.

Thermo-plastic adhesive is applied to the upper and inner face of the blank 14 and is disposed 20 in parallel strips adjacent the side edges 15. The adhesive also extends between the score lines 21 and the top edge 17 of the blank and across the upper part of the blank adjacent and above the score line 22. This provides side adhesive end 25 strips 35 and an irregular end strip 36, 37.

The strip 37 is of substantially the same width as the strips 36 and this leaves uncoated flap parts 38, 39 of the blank at its upper end. This adhesive may be of any suitable material but is 30 preferably of a thermo-plastic nature which when applied to the blank is allowed to harden or dry.

The blank 14 is folded into body form along a plurality of spaced parallel creases 41 so that 35 when formed the blank is divided into a front wall 42 which includes the removable area 33, a bottom 43, a back wall 44, and a top 45 which includes the weakened sections 26 and a substantially triangular-shaped flap 46 having the score 40 lines 21, 22. The flap 46 extends down and adjacent the front wall 45 and is secured thereto to form the open-ended tubular body 11.

The body is completed by pressing the overlapped flap and front wall parts together while 45 heating or otherwise causing the adhesive strip portions 36, 37 to become plastic so that the ends of the blank are stuck together. This leaves the end 38 of the flap 46 free from the body front wall 45, the adhesive part 36, 37 forming a seal with 50 the front wall by adhering to the removable area 33 which is enclosed within the score lines 28, 29, 31, 32.

Each end member 12 is preferably formed from a flat blank 51 (Fig. 3) which in the construction shown in the drawings is square and which is 55 provided with notched outer corners 52. These notches provide flange parts 53 which are bent at right-angles to the blank along creases 54. The end members when inserted into the open ends 60 of the body have their flange parts 53 extending outwardly.

It is convenient to insert and secure one end member 12 into one open end of the tubular body preparatory to filling. The flange parts 53 of the 65 inserted end and the marginal end portions 15 of the formed body are pressed together while heating or otherwise causing the adhesive strip portions 35 to become plastic so that the end member 12 is first stuck in place. The engaged 70 sections of the end member and the body are then locked together by a plurality of indentations 56 (Figs. 1, 2, 4, 7 and 8).

At each indentation the contacting walls of the assembled parts are sheared or cut through 75 along short, parallel and spaced lines 57 (Fig. 8).

Between the sheared lines 57, the wall parts are laterally displaced outwardly and inwardly, in curved sections 58 which extend across the adhesive joint connecting the parts together as clearly shown in Fig. 8. This displacement of the 5 wall parts locks the walls together.

When one end member 12 is attached to the body 11 the container thus formed is ready for filling. The drawings show crackers or the like by way of illustration of such contents. The 10 filled container is then closed by inserting the second end member 12 into its filling or open end. The second end member is stuck and then locked in place in the same manner as with the opposite end already described. The flanges 53 being on 15 the outside permit shearing and interlocking of the parts by manipulation from the exterior and therefore this may be done, as described, after the container is filled.

Opening of the container is effected by lifting 20 the flap 46, utilizing the unsecured portion 38 as a finger hold. This lifting of the flap causes the fibres of the removable area 33 in the front wall 42 to separate or tear away thereby readily breaking the seal at flap and front wall. The score 25 lines 28, 29, 31, 32 serve as barriers to restrict this tearing action to the removable area and prevent the zone of tear from extending into the wall on either side of the removable area.

In case the fibres of the flap 46 should tend 30 to tear away during this operation, its score lines 21, 22 serve as a barrier to prevent the zone of tearing from extending into the unsecured part 39. In any event the score lines 28, 29, 31, 32 and the auxiliary score lines 21, 22 direct the zone 35 of tearing into the weakened sections 26 in the top wall 45. This causes the fibres of the top wall 45 to separate between the score lines 18, 25 thereby releasing the central portion of the wall which is set off between the weakened sections 26. 40

The released portion of the top wall is utilized as a cover or reclosure member 61 which may be hinged on its connection with the back wall 44 along the crease 41 as shown in Fig. 2 to gain access to the interior of the container. The separation of the fibres at the score lines 18, 25 provides stepped ledges 62 (Figs. 2 and 6) which are utilized, when the cover is again brought into reclosure position, to prevent the cover from being forced into the interior of the container. 50

It is thought that the invention and many of its attendant advantages will be understood from the foregoing description, and it will be apparent that various changes may be made in the form, construction and arrangement of the parts 55 without departing from the spirit and scope of the invention or sacrificing all of its material advantages, the form hereinbefore described being merely a preferred embodiment thereof.

I claim:

1. A fibre container comprising a body member having an opening element, the latter being secured by means of adhesive to said body member and providing a sealed joint, said adhesive being interposed between the engaged parts in a restricted zone, and a score line formed in each of said engaged parts and located adjacent a marginal edge of the adhesive to constitute a barrier which prevents spreading of the tearing area into said body member and said opening element when the sealed joint is broken, as when opening the container. 65

2. A fibre container comprising a body member having an opening element, the latter being secured by means of adhesive to said body member 70

and providing a sealed joint, said adhesive being interposed between the engaged parts in a restricted zone, and score lines formed in each of said engaged parts and setting off removable areas to facilitate breaking the joint when opening the container and to provide barriers which prevent spreading of the tearing area into said body member and said opening element when the sealed joint is broken.

10 3. A fibre container comprising a body member having an opening element, the latter being secured by means of adhesive to said body member and providing a sealed joint, said adhesive being interposed between the engaged parts in a restricted zone, a score line formed in one of said engaged parts and located adjacent a marginal edge of the adhesive, and other cooperating score lines formed in the other of said engaged parts and setting off a removable area which includes 15 the restricted zone of the adhesive, said score lines facilitating breaking of the sealed joint when opening the container and providing barriers which prevent spreading of the tearing area when the sealed joint is broken.

20 4. A fibre container comprising a body member having an opening element hingedly connected thereto and including a flap overlapping a wall of said body member, the flap being secured by means of adhesive to said body member wall and 25 providing a sealed joint, said adhesive being interposed between the engaged parts in a restricted zone, and a score line formed in each of said engaged parts and located adjacent a marginal edge of the adhesive to constitute a barrier which 30 prevents spreading of the tearing area into said body member and said opening element when the sealed joint is broken as when opening the container.

5. A fibre container comprising a body member 35 having an opening element, the latter being secured by means of adhesive to said body member and providing a sealed joint, said adhesive being interposed between the engaged parts in a restricted zone, score lines disposed in a wall of said body member adjacent the engaged parts and forming weakened sections in said wall, and a score line formed in one of said engaged parts and located adjacent a marginal edge of the adhesive to constitute a barrier which prevents 40 spreading of the line of tear when the sealed joint is broken as when opening the container and which also directs the line of tear into the weakened sections in said adjacent wall whereby a portion of the adjacent wall is released to permit access to the interior of the container.

55 6. A fibre container comprising a body member having an opening element, the latter being secured by means of adhesive to said body member and providing a sealed joint, said adhesive being interposed between the engaged parts in a restricted zone, score lines disposed in a wall of said body member adjacent the engaged parts and forming weakened sections in said wall, and a score line formed in one of said engaged parts and located adjacent a marginal edge of the adhesive to constitute a barrier which prevents 60 spreading of the line of tear when the sealed joint is broken as when opening the container and which also directs the line of tear into the weakened section in said adjacent wall whereby a portion of the adjacent wall is released to permit access to the interior of the container, said released portion being hingedly connected with the body member and producing a reclosure cover for the container.

7. A fibre container comprising a body member having an opening element, the latter being secured by means of adhesive to said body member and providing a sealed joint, said adhesive being interposed between the engaged parts in a restricted zone, score lines disposed in the inner and outer surfaces of a wall of said body member adjacent the engaged parts and forming weakened sections in said wall, and a score line formed in one of said engaged parts and located 5 adjacent a marginal edge of the adhesive to constitute a barrier which prevents spreading of said tearing area when the sealed joint is broken as when opening the container and which also directs the tearing into said weakened sections to 10 rupture them whereby a portion of said adjacent wall is released to permit access to the interior of the container, said released portion of said adjacent wall being hingedly connected with the body member and producing a reclosure cover 15 for the container, the rupture of said weakened section producing ledges which prevent entrance of the cover into the container when the cover is in reclosure position.

20 8. A fibre container comprising a tubular body member including a cover portion having a flap overlapping and adhesively secured to an adjacent wall of said body member to provide a sealed joint, and transverse score lines disposed in said cover portion adjacent the opposite ends 25 thereof to set off and define opposite edges of said cover portion, said score lines being adapted 30 to be ruptured after the sealed joint is broken by raising said flap to permit the cover portion to be hinged outwardly relative to said body member, said body member having end wall members provided with flanged portions inter-indented with and permanently secured to said body member to reenforce the latter against strains when the adjacent score lines are ruptured to release said cover portion. 40

9. A fibre container comprising a one-piece tubular body member having overlapped and engaging parts secured together by means of adhesive and providing a sealed joint, said adhesive being interposed between the engaged parts in a restricted zone, a score line formed in one of said engaged parts and located adjacent a marginal edge of the adhesive to constitute a barrier which prevents spreading of the tearing area when the sealed joint is broken as when opening the container, and additional score lines disposed on the opposite surfaces of said engaged part adjacent the opposite ends thereof to set off and define opposite edges of a cover portion, said last mentioned score lines being adapted to be ruptured during breaking of the sealed joint to permit said cover portion to be hinged outwardly relative to and along an unscored portion of said body member, and separate flanged end members for closing the ends of the container and adapted to be assembled with the body member after the latter is formed and after its overlapping parts are secured together, and indentations in the contacting portions of said assembled body and end members, said indentations having sheared sections separated by laterally displaced sections which engage across the junction between the flanges of the end members and the body member to interlock the same, said interlocked construction reenforcing the body member against distorting strains when the adjacent score lines are ruptured to release said cover portion. 65 70
